J. HOFFMANN.

REVERSIBLE ENVELOPE.

No. 321,297.

" Patented June 30, 1885.

UNITED STATES PATENT OFFICE.

JACOB HOFFMANN, OF CINCINNATI, OHIO.

REVERSIBLE ENVELOPE.

SPECIFICATION forming part of Letters Patent No. 321,297, dated June 30, 1885.

Application filed December 30, 1884. (Model.)

To all whom it may concern:

Be it known that I, JACOB HOFFMANN, of Cincinnati, Hamilton county, Ohio, have invented a new and useful Improvement in Re- 5 versible Envelopes, of which the following is a specification.

My invention relates to a reversible safety-envelope that comprises the following features: A pouch, bag, or pocket, whose mouth-margin, 10 having been pasted externally and folded over so as to make a double-ply lip, is creased at two places and doubly perforated, and being folded twice over receives a tape, by which, in connection with such creasing and folding, 15 it is enabled to securely retain any description of dry contents however finely divided —such, for example, as the smallest grain or seed, or any kind of powder. The sheet of paper or blank out of which the envelope is 20 formed extends in the shape of a leaf or fly whose obverse and reverse faces are capable of alternate use for the respective addresses of the shipper and the consignee. Wings upon the sides of this fly, having suitable orifices and 25 fastening-tape, enable the fly to be temporarily secured with either address exposed to view at will of the sender for the time being, or of being unfastened with the facility prescribed for open mail-matter. The "blank" out of 30 which this envelope is made consists of a single sheet of manila or other tough paper cut to the peculiar form hereinafter represented.

In using the device, the material to be mailed is deposited in said pocket, whose mouth is then folded twice over and tied down. 35 Accurate folding, so as to bring the eyelets in register for the fastening-tape, is facilitated by the well-defined shoulder of the aforesaid two-ply portion, formed by pasting together 40 in the manner stated. The construction is such that the folded and tied wings co-operate with the folded and tied bag-mouth to securely seal the receptacle against any possible accidental escape of contents, without opposing 45 any difficulty in the way of their examination by the postal authorities.

In the accompanying drawings, Figure 1 represents an envelope embodying my invention, the package being shown open, and having 50 that side visible which bears the shipper's address. The dotted lines in this figure indi-

cate the contour of the blank out of which the envelope is formed. Fig. 2 represents the same envelope with its pocket closed, and with that side presented which is to receive 55 the address of the consignee. Fig. 3 shows the package closed. Fig. 4 is an enlarged section of the bag-mouth or opening of the pocket.

The broken lines in the several figures indicate creasing-places.

I provide a blank of manila or other kind of tough paper, so cut out of a single rectangular sheet as to present the contour indicated by the dotted lines A in Fig. 1. Paste being applied to the surfaces a, a', and a'', the portion 65 a is turned back on itself so as to form a two-ply thickness at a. The flaps B' B'' are then overlapped and made to adhere to each other at a and to the blank B by their pasted portions a'', so as to form a pouch, bag, or 70 pocket, C, of which the said two-ply edge constitutes the mouth-margin. At each side of this marginal portion are two orifices or eyelets, D. Previous to being folded and made 75 to adhere, as above, the part a' is made to receive two orifices, D', into which is drawn a tape or string, E. The prolongation or flap F has two wings, G G', of which the wing G has two eyes or orifices, D'', for a tape or tie, 80 E, one of whose ends is capable of engagement in an orifice, D'', in the other wing. The orifices D'' D D'' may be protected by re-enforces or by metallic eyelets. The entire appendage F G G' is designed to afford places on its ob- 85 verse and reverse faces for two distinct ad- dresses, one face (seen in Fig. 2) being devoted to the addresses of the consignee, which are usually written, and the other face (seen in Fig. 1) carrying the shipper's address, which may be permanently imprinted. The con- 90 signee-face of the envelope having been ad- dressed, and the pocket having been charged with the goods or samples, the lips of the bag are pressed together and are twice folded at the already-formed crease-marks 1 2, and then 95 tied, as seen at Fig. 2. The address-flap is then folded back against the bag, and its two wings brought round in front of the same and tied, as shown in Fig. 3. It is manifest that when thus folded and tied the wings assist in 100 holding down the folded lips of the bag-mouth flat against the bag, and that they also aid in

closing the corners 3 4 against any escape of contents. The pasted overlap of the parts a' and the eyelets D' enable secure fastening of the string E, and said overlap also strengthens 5 the material at the orifices D.

I claim as new, and of my invention—

The reversible retentive safety-mailing envelope, consisting of the reversible bag, pouch, or pocket C, whose mouth is adapted to be se-
10 cured in the described infolded condition by the fastenings D D' E, and having at its bot-

tom the integral prolongation F, with places for two distinct addresses on its obverse and re-
verse faces, and whose reversible closing wings G G', are provided with the fastenings D'' D''' 15 E', substantially as set forth.

In testimony of which invention I hereunto set my hand.

JACOB HOFFMANN.
